UNITED STATES PATENT OFFICE

GEORGE WASHINGTON NEWMAN, OF CHICAGO, ILLINOIS, ASSIGNOR TO WILSON-JONES CO., A CORPORATION OF MASSACHUSETTS

LOOSE-LEAF BINDER

Application filed October 18, 1926. Serial No. 142,351.

This invention relates to a loose leaf binder of that type involving impaling posts which are removably hinged to the cover thereof.

5 The problem sought to be solved in connection with a binder of this type consists in combining the hinge strips and impaling posts with a thin flexible cover in such a way that there is little or no liability of the 10 cover being torn through use, or the hinge strips becoming disassociated from the cover.

The invention comprises the novel structure and combination of parts hereinafter described and more particularly pointed out 15 and defined in the appended claims.

In the accompanying drawings which illustrate a preferred embodiment of this invention and in which similar reference numerals refer to similar features in the different views:

Figure 1 is a perspective view of a loose leaf binder involving this invention.

Figure 2 is an enlarged fragmentary transverse sectional view of the binder.

25 Figure 3 is a view similar to Figure 2 excepting that it is taken in the plane through an impaling post.

Figure 4 is a fragmentary sectional view taken upon the line IV-IV of Figure 3.

30 Figure 5 is an enlarged fragmentary interior view of the binder.

In the exemplification of this invention there is shown a binder consisting of a flexible cover 1 which may be made of leather 35 or imitation leather, or any other suitable material. A pair of hinge strips 2 provided with curled eyeleted portions 3 at one margin thereof are provided. These hinge strips are suitably slotted, as indicated at 4, for a purpose that will presently appear. These hinge strips are applied at spaced 40 points upon the interior side of the cover 1 and are longitudinally directed with the curled eyelets projecting rearwardly. They are secured or combined with the cover by means of plates 5 sheathed in fabric or the like which are applied to the outside of the cover and which are provided with tangs 6 45 which extend through the cover and through

the slots 4 and are bent or crimped over the hinge plates 2.

The curled eyelet 3 on each hinge strip is cut away at spaced points for receiving the end of impaling posts 7 which are provided with eyelets at their ends for receiving the locking rods 8 which are slidably mounted in said eyelets. 55

It will be evident that if an attempt were made to secure hinge plates to a thin flexible cover without the use of the sheathed plates 5 the cover would soon be torn or worn out at the point of connection with the hinge plates. It will, therefore, be evident that according to this invention it is 60 possible to use a thin flexible cover in the construction of such a binder by attaching the hinge plates as herein set forth. 65

I am aware that many changes may be made, and numerous details of construction 70 may be varied through a wide range without departing from the principles of this invention, and I therefore do not purpose limiting the patent granted hereon, otherwise than necessitated by the prior art. 75

I claim as my invention:

1. In a loose leaf binder, a flexible cover, a pair of hinge strips interiorly of the cover, a pair of sheathed plates exterior of the cover, and tangs on said sheathed plates extending through said cover and through said 80 hinge plates for combining the latter with the cover.

2. In a loose leaf binder, a one piece flexible cover, a pair of hinge plates interiorly of the cover, each plate having an eyeleted margin and spaced slots, an anchor plate superposed over each hinge plate upon the exterior side of the cover, and means cooperating with said slots for securing each 85 anchor plate to the underlying hinge plate. 90

In testimony whereof I have hereunto subscribed my name.

GEORGE WASHINGTON NEWMAN.
